(No. 947)

Goymred Thulmeyer's Design for Coal Shovel

Patented Oct. 6, 1857

UNITED STATES PATENT OFFICE.

GOTTFRIED THÜLEMEYER, OF NEW YORK, N. Y.

DESIGN FOR A COAL-SCUTTLE.

Specification forming part of Design No. 947, dated October 6, 1867.

To all whom it may concern:

Be it known that I, GOTTFRIED THÜLEMEYER, of the city, county, and State of New York, have invented or produced a new and ornamental Design for a Coal-Scuttle; and I do hereby declare that the following is a full, clear, and exact description of the same, reference being had to the annexed drawings, making a part of this specification, in which—

Figure 1 is a side view of a coal-scuttle constructed according to my design. Fig. 2 is a transverse vertical section of the same, taken in the line *x x*, Fig. 1.

Similar letters of reference indicate corresponding parts in the two figures.

A A represent the two sides of the scuttle, which are parallel with each other, and have each a series of curved projections, *a*, formed on them, so disposed as to represent a testaceous shell of well-known form, as shown in Fig. 1. Both sides A A are precisely the same, and are connected at the upper and back ends by a convex end strip, B, which gradually assumes a plane surface as it approaches the bottom of the scuttle, as shown at B', Fig. 2, the

plane form extending to the front end of the scuttle. The end strip, B, has a scroll projection, *b*, attached, which forms the tilting handle, and two curved projections, *c c*, one attached to the lower end of each side, which projections are connected to cylindrical transverse pieces, *d*, which form the feet of the scuttle. The front ends of the side pieces, A A, terminate in plates *e*, which have sunken panels *f*, the outer ends of the plates being curved and having a lid, C, fitted on them, the back end of said lid being connected by a joint or hinge to the body of the scuttle, as shown at *g*.

D is a bail or handle, which is attached to the body of the scuttle and at its upper part.

What I claim as new, and desire to secure by Letters Patent, is—

The general configuration of the parts, as herein shown and described, the whole forming a new and original design for a coal-scuttle.

GOTTFRIED THÜLEMEYER.
